UNITED STATES PATENT OFFICE.

OTTO W. SCHAUML, OF PHILADELPHIA, PENNSYLVANIA.

MECHANISM FOR HARDENING METAL BALLS.

1,054,038.

Specification of Letters Patent. Patented Feb. 25, 1913.

Application filed July 27, 1912. Serial No. 711,830.

To all whom it may concern:

Be it known that I, Otto W. Schaum, a citizen of the United States, residing in the city of Philadelphia, county of Philadelphia, and State of Pennsylvania, have invented an Improvement in Mechanism for Hardening Metal Balls, of which the following description, in connection with the accompanying drawings, is a specification, like letters on the drawings representing like parts.

The invention to be hereinafter described relates to mechanism for hardening metal balls, and more particularly such balls as are to be subsequently employed for anti-friction purposes. In order that metal balls of this general type may properly withstand the excessive wear and strains to which they are subjected in use, they must not only be homogeneous and uniform in character, but they must be properly and uniformly hardened, and with this general object in view the aims and purposes of the present invention are to provide means, simple in construction, efficient and reliable in operation, whereby metal balls may have imparted to them the desirable hardened character, all of which will best be made clear from the following description and accompanying drawings of one form of device for carrying the invention into practical effect, it being understood that the invention is not necessarily restricted to the particulars or details of such device, but in its true scope is defined by the claims.

In the drawings:—Figure 1 is a side view of a machine or apparatus embodying a convenient form of devices for carrying the invention into effect, some of the parts being broken away; Fig. 2 is a section on the line 2—2, Fig. 1; Fig. 3 is a section on the line 3—3, Fig. 1 with parts broken away; Fig. 4 is an enlarged longitudinal sectional view of a revolving furnace or heating device for uniformly heating the balls; Fig. 5 is an enlarged detail showing an adjustable feeding device for feeding metal balls to the furnace or heating device; Fig. 6 is a section on the line 6—6, Fig. 4, showing one means for discharging the heated balls from said furnace and directing them to the quenching mechanism; Fig. 7 is a sectional view at the feed end of the furnace or heating device, showing how the balls are fed uniformly and in proper quantities to be heated; Fig. 8 is a section on the line 8—8, Fig. 7,

showing the measuring device feeding a proper quantity of balls to the furnace; and Fig. 9 is a view similar to that of Fig. 8, parts being broken away showing the measuring feeder scooping up balls to be fed to the furnace.

In order that the balls may be uniformly heated the present invention contemplates that they be subjected to the action of the heating medium so that the latter may act equally on all the balls submitted thereto, and as one form of means to this end, a furnace A preferably of cylindrical form, is provided and the heating medium is introduced at one end and the balls at the other, suitable means being provided for slowly turning the cylindrical furnace and traveling the balls gradually lengthwise thereof in a single layer.

In the present form of the invention, a suitable supporting frame 1 has mounted thereon the cross pieces 2, Fig. 1, carrying bearings 3 for a shaft 4, driven by a worm wheel 5, which derives motion from a worm 6, Fig. 4, on a transverse shaft 7 which, in turn, may be driven from any suitable or convenient source of power. Preferably two shafts 4, Fig. 6, are employed, each having wheels or carrying rolls 8, on which rests the cylindrical furnace A, suitable bands 9 about the furnace serving to engage the wheels or rolls 8; the construction being such that as the shafts 4 rotate they turn the furnace A in a manner that will be well understood.

The furnace A comprises a metal shell 10 lined with a suitable heat-resisting material 11, such for instance, as fire clay. At one end, the left, (Figs. 1 and 4) the cylindrical furnace is provided with an opening 12 through which the heating medium, such as gas or other desirable fuel may be passed into the furnace, but as such feature of the furnace may be of any general character and is well understood in the art, further detail description thereof is unnecessary, the essential being that the cylindrical furnace A shall have introduced longitudinally or lengthwise, a suitable ball heating medium. At the opposite end the furnace has a cap 13, also suitably lined with fire clay or other heat-resisting material, and extending through said cap is the feed opening 14 for the balls to be treated. Secured to the cap 13, as by bolts 15, Figs. 8 and 9, is the feed snout 16 of the general character indi-

cated by Fig. 8, said snout 16 having a side entrance 17 through which the balls may be fed, as will more fully appear. Secured to the outer portion of the cap 13 is the wall 18 preferably, though not necessarily, of conical form, and serving to provide a feed chamber 19 at the feed end of the furnace.

Mounted on a suitable support 20, Figs. 1 and 4, extending from the frame 1, is the ball-charging device, preferably formed as a metal casing 21, the edges 22 of which overlap the adjacent edge of the feed chamber wall 18, as best shown by Fig. 4, the construction being such that as the cylindrical 15 furnace is revolved and with it the wall 18, there will be maintained between the feed chamber 19 and the ball-charging device an uninterrupted communication for the passage of balls from the charging-device into 20 the feed chamber.

In order to facilitate the passage of the balls into the charging device, the latter may be provided with a spout or mouth 23, the opening in which may be conveniently opened 25 and closed by a valve 24, Fig. 4. If desired, the device may be otherwise connected to the feed chamber, the only essential being that balls fed to the charging device may readily find their way into the bottom of the feed 30 chamber 19, where they remain during the revolution of the furnace and feed chamber by virtue of gravity until taken therefrom by the measuring feeder, which will now be explained.

Passing through the wall 18 of the feed chamber is the measuring feeder shown as a scoop like the device 25 having a lip 26 projecting into the feed chamber. Mounted to slide in the scoop 25 is a block or slide 27 40 screw-threaded to the adjusting stem 28, Figs. 5, 7, 8, and 9, which is provided with a hand wheel 29, whereby the slide 27 may be adjusted to different positions in the scoop and thereby regulate or measure the number 45 of balls that will be taken up by the scoop as the furnace and feed chamber wall 18 rotate. A convenient form of such measuring feeder is indicated by Fig. 5, and as therein shown the slide 27 may have secured thereto 50 a gage 30 having marks 31 thereon to indicate the quantity of balls in the measuring feeder for a purpose that will presently appear.

From the construction thus far described, 55 it will be noted that as the feed chamber and furnace rotate, the scoop 25 will scoop up from the bottom of the chamber a quantity of balls, dependent upon the adjustment of the slide, 27, as indicated by Fig. 9; and 60 as the rotation continues the balls will be carried upward, as indicated by Fig. 8, until they roll out of the measuring feeder or scoop 25 over the lip 26 and drop into the side opening 17 of the feed snout 16 from 65 which they pass by gravity into the furnace.

As hereinbefore noted, it is desirable that the balls be uniformly and thoroughly treated, and to this end it is desirable that only sufficient balls be fed into the furnace at one time to insure that they arrange 70 themselves in a single layer, and that this single layer formation be maintained as the balls roll and rotate in their movement to the discharge end. Obviously, therefore, the number of balls introduced by the measuring feeder will be dependent upon the size 75 of the balls, a greater number of small balls being susceptible of the desired single layer treatment than larger ones at any one charging.

In order to maintain the balls in single layer and prevent over-riding and to cause them to travel lengthwise of the furnace, the furnace A is provided with an internal spiral 32, Fig. 4, projecting beyond the surface of the fire clay lining 11, such spiral being preferably formed as a rib extending from the casing 10, though any other spiral rib formation that will serve the intended purpose may be employed. It will be noted 80 that the balls are introduced to the furnace at the end opposite the fuel supply and in measured quantities to permit and maintain a single layer formation regardless of the size of the balls, and that they are thus 85 gradually and progressively subjected to the final temperature desired, while uniform treatment is assured to all of the balls alike and at all parts of each as they roll and turn in single layer during their travel.

When the properly heated balls have reached the discharge end of the furnace it is desirable that a proper quantity of such balls will be then discharged into the quenching portion of the apparatus, and here again the present invention contemplates a proper quenching by still restricting the number of balls to such treatment that the treatment may be of the same uniform character as marked the heating operation. At the end of the furnace, opposite that into which the balls were originally fed, there is provided a discharge opening for the balls, best indicated by Figs. 4 and 6. This opening may be preferably formed as indicated in Fig. 6 wherein is provided the lining 33 having substantive lip portions 34 to coact with a door 35 which may be formed as indicated in Fig. 6 and to prevent burning may be made hollow. This door is preferably supported on the links 36 pivoted at 37 to the furnace. Since the furnace is to be revolved during the heating operation upon the balls, it is desirable that the door 35 be held in place and prevented from opening at undesired times. To this end any suitable means may be employed, but the present invention contemplates a bail or projection 38 secured to the door 35 and adapted to ride upon a guide or track.

way 39 when the furnace in its rotative movement carries the door toward the discharging part. This guide or trackway may extend either part way around the furnace or entirely around the same, if desired, but in any event, the lower end portion thereof ends at a point 40 which, when reached by the bail 38 permits the bail 38 to drop from said guide or trackway and force admit 10 the door 35 to move downward or in a direction to open the same, thereby permitting such balls as have been moved longitudinally of the furnace by the spiral ribs 32 into a position adjacent the door to drop 15 through said opening into a chute 41, the upper portion of which preferably extends around the discharge portion of the furnace and is supported from the machine frame 1, as indicated in Figs. 1 and 6. After the 20 balls have been thus discharged by the opening of the door 35, it is desirable that the door be automatically closed, and the present invention contemplates the provision of a closing device for thus automatically closing 25 the door after the discharge of balls has been permitted to pass from the furnace. As one form of said automatic closing means, the wall of the chute 41 is provided with a metal or other door controller 30 43, Fig. 4, the lower end 44 of which is adapted to receive the bail 38 as the door swings on the links 36 into open position, and as the rotation of the furnace gradually carries the door upward, the bail 38 is 35 adapted to ride upon and contact with the upper portion 45 of the closing device, whereby the door is finally seated.

Adjacent the discharge opening of the furnace it is desirable, in some cases at 40 least, to provide an accumulator, that is, a device which will, as the furnace rotates, accumulate or gather those balls which at each rotation of the furnace, are contained between the adjacent ribs 32 and which have 45 been properly heated during their travel to the discharge portion of the furnace. This accumulator 46 is preferably formed as a pocket or abutment, as indicated by Fig. 4 and Fig. 6, which will insure that the balls 50 be gathered upon the door 35 during rotation of the furnace. This particular feature 55 of the invention has been found convenient and practical in operation, but it is to be understood that the invention is not necessarily restricted thereto, and that in some cases it may be dispensed with altogether.

The chute 41 extends downward from the discharge end of the furnace A and at its lower portion has two discharge spouts, 47 60 and 48, leading in generally opposite directions and provided with a valve 49, whereby the balls discharged into the chute may be directed into either one of the discharge spouts 47, 48, and suitable means may be 65 employed for operating the valve 49, but

such means being a well understood device, it is not herein illustrated.

Disposed in operative relation with the furnace A and preferably beneath the same, is a tank 50, Figs. 1, 2, and 3 in which is 70 mounted the circulating drum. In the present form of the invention, the circulating drum is formed as a substantial cylindrical body 51, Figs. 1, 2 and 3, mounted on a shaft 52 which may be suitably supported 75 by appropriate bearings in the end walls of the tank 50 or by other suitable means, not necessary to describe, and, rotative movement may be imparted to the circulating drum by suitable means, as for instance, by 80 appropriate belting attached to a pulley 53 on the end of the shaft 52, but as such means for rotating a drum are well understood, further elucidation of this feature is unnecessary. 85

To appropriately support the quenching drum upon the shaft 52, suitable spiders or radial arms 54 may be employed, it being noted that the ends of the quenching drum are open, as will hereinafter more fully 90 appear.

Projecting from the interior surface of the quenching drum and extending spirally throughout the length thereof is the rib 55, Figs. 1 and 2, said spiral feeding rib 55 being arranged to feed the balls lengthwise 95 of the quenching drum from left to right, viewed in Fig. 1.

As hereinbefore noted, the end portions of the quenching drum 51 are open, and through the open end at the left, (Fig. 1) projects the feed spout 48, leading from the chute 41, said feed spout having its discharge end well within the drum, as indicated in said Fig. 1, so that balls delivered 100 therefrom will fall to the right of the first spiral of the feed rib 55. As the quenching drum rotates the feed spiral 55 therein will act to move the balls lengthwise of the quenching drum 51 to the opposite or discharge end thereof, and during such feeding motion, the balls will be subjected to 105 the continuous action of the quenching liquid contained in the tank 50. 110

As well understood by those skilled in the art, when a highly heated ball is suddenly dropped in a liquid such as water, there is formed about the ball a zone of steam or vapor which for a time protects the ball from the cooling action of the liquid 115 in which it is immersed. The effect of this zone of steam or vapor is to prevent proper and uniform hardening of the ball, and the present invention contemplates means for overcoming this objectionable 120 condition and to subject the balls to such treatment that the zone of steam or vapor heretofore formed about the ball will be dissipated and the full action of the cooling liquid be transmitted to the ball direct 125 130

and at all points. Hereinbefore, while referring to the treatment of the balls by the furnace and the quenching drum, it has been stated that the balls should be prevented, as far as possible, from piling one upon the top of another so that each ball shall receive its proper treatment unprotected by other balls. To maintain this properly separated condition the spout 48 leading into the end of the quenching drum, Figs. 1 and 2, is preferably formed sufficiently large to permit the full number of balls transmitted thereto to roll therefrom in single layer formation into the quenching drum. In the present form of the invention, in this respect, the spout 48 is divided, as indicated in Fig. 2, in order to straddle the shaft 52 of the quenching drum, but it is obvious that it might be made in the single form, if desired.

As the balls are discharged from the spout 48 into the quenching drum in the manner hereinbefore noted, they are directed beneath the surface in the water of the tank 50 by the spout 48, and will have produced upon themselves the objectionable zone of steam or vapor. In order to remove this, and permit the balls to be uniformly cooled throughout their entire extent, the present invention contemplates projecting against the balls as they are discharged from the spout 48 into the quenching drum, a stream of water or other quenching liquid, and as one means to this end there is provided a nozzle 56 adjoint each opening of the spout 48, as clearly indicated in Fig. 2. These nozzles 56 are preferably flattened somewhat so that the stream of quenching liquid which is directed against the balls as they fall from the spout 48 will be distributed over the entire series of balls discharged therefrom. This forceful action of the quenching liquid directed from the nozzles 56 directly against the heated balls serves to dissipate and drive from around the balls the objectionable zone of vapor or steam and to permit each of the balls to be thoroughly treated throughout its entire superficial area to the action of the moving liquid while the balls themselves are kept in motion rolling in a manner to insure that all parts of the balls may be properly treated.

It will be understood that as the balls come down the spout 48 and the entire quenching drum between the feed spirals 55, they are in active rolling motion and as they strike the lower supporting surface of the quenching drum, this rolling activity is still maintained, consequently the blast or stream of water or other quenching liquid directed by the nozzles 56 and treating the balls at all parts thereof, eliminates effectively the objectionable zone of steam or vapor which might otherwise be formed.

Any suitable form of liquid supply, pref-

erably water, may be directed through the nozzles 56, but in the present form of the invention the nozzles 56 are shown as connected by a pipe 57, Figs. 1 and 2, to a pipe 58, extending transversely of the quenching tank 50 and being itself connected to an upwardly extending pipe 59. Connected to the pipe 59 are the two conduits or pipes 60 and 61 provided with a suitable hand valve 62. One of these pipes may, if desired, lead to a supply of cold water, as for instance the pipe 60, and the other of these, as for instance the pipe 61, may lead to a supply of hot water, whereby the temperature of the quenching liquid may be adjusted to suit the conditions of use by a simple manipulation of the hand valves 62.

Extending from the pipe 59 is a circulating pipe 63, Fig. 1, connected at 64 with the discharge pipe 65, the lower portion of which is connected to a suitable pump 66 which may be itself in circulating communication with the quenching tank 50. In the circulating pipe 63 is the hand valve 67 and a similar valve 68 is provided in the discharge pipe 65, whereby, upon proper manipulation of these respective hand valves the pump 66 may be caused to circulate the liquid in the desired course.

As hereinbefore noted, both ends of the quenching drum 51 are open, and extending into the discharge end, at the right (Fig. 1) of the drum, is a trough 69. At the discharge portion of the quenching drum are a series of buckets 70 which, as the balls are fed lengthwise of the quenching drum by the feeding ribs 55, serve to coat and carry the balls upward from the lower part of the quenching drum to a point directly over the trough 69 or a portion thereof, and upon further rotation of the drum to discharge the balls into the said trough 69 whereby they are carried from the machine and delivered to a proper receptacle.

From the general character of the invention described with relation to the illustrated means for carrying it into practical effect, it will be apparent that the balls to be hardened are first uniformly heated in a manner to subject each of the balls to the gradually increasing temperature effect, until the balls, having been appropriately and uniformly heated, are discharged in proper quantities into the quenching portion of the apparatus, where they are directed beneath the quenching liquid. As they thus meet the quenching liquid, it will be noted that a stream of water or other liquid is directed against the balls while the latter are in active rotative movement, whereby each of the balls is subjected to treatment which eliminates therefrom the formation of a zone of steam or vapor and insures proper and uniform hardening of the ball throughout its entire extent. As the balls become

cool, in the manner stated, they are carried lengthwise of the quenching drum by the rotation of the latter and delivered therefrom in proper hardened condition.

5 Throughout the treatment, as will be apparent, the balls are fed to the furnace in suitable quantities to insure that the series of balls between the feeding ribs of the furnace will maintain a single layer formation 10 as they travel lengthwise of the furnace, thus insuring that each one of the balls during its rotative movement, shall be uniformly and fully treated and that all balls shall be treated alike. It will also be apparent 15 that this same predetermined quantity of balls upon each rotation of the furnace is delivered into the quenching portion of the apparatus, where they are not only quenched or treated by the quenching liquid, but in virtue of their predetermined number and the forceful direction upon them of the quenching liquid, they are uniformly hardened throughout.

It will be obvious that various changes 20 may be made in the details for carrying the invention into practical effect, and with this in mind, the invention is clearly pointed out by the claims.

What is claimed is:—

30 1. In a quenching apparatus for metal balls, the combination of a furnace for uniformly heating the balls, a quenching tank, means for directing the heated balls from said furnace to said tank, and means extending into the quenching tank adjacent the point where the balls are received for forcing a stream of liquid upon the balls when they reach the quenching tank.

2. In a quenching apparatus for metal 40 balls, the combination of a furnace, a quenching tank associated with said furnace, means for directing the heated balls from said furnace to said tank, means for causing the balls to turn in said tank, and a liquid conduit having an opening within the quenching tank for directing a stream of liquid upon the balls at the point where they are received from the furnace for dissipating the zone of steam or vapor formed 45 about the balls as they are treated by the quenching liquid in the tank.

3. In a quenching apparatus for metal balls, a furnace for heating the balls, a quenching tank, a quenching drum in said 50 tank, means for directing the heated balls into the quenching drum, and means for forcing a stream of liquid through the end of the quenching drum and upon the balls as they reach the quenching drum.

4. In a quenching apparatus for metal 55 balls, a furnace for heating the balls, a quenching tank, a quenching drum in said tank, means for revolving the quenching drum, means for directing the heated balls 60 into the quenching drum, and means includ-

ing a nozzle for forcing a stream of liquid in a general direction longitudinally of the quenching drum and upon the balls as they reach the quenching drum.

5. In a quenching apparatus for metal 70 balls, the combination of a heating furnace, a quenching tank, a quenching drum in said tank and having an open end, means for rotating the quenching drum, means for directing heated balls from said furnace into said revolving drum, and a nozzle extending 75 into the open end of the revolving quenching drum for directing a stream of liquid upon the heated balls as they are delivered to the quenching drum.

6. In an apparatus of the class described, the combination of a furnace for heating metal balls, a cylindrical quenching drum disposed below the furnace, means for rotating the drum, means for directing heated 80 balls from the furnace into the quenching drum, and a nozzle extending into the quenching drum adjacent the point where the balls are received by said drum for directing a stream of liquid directly upon the 85 balls and preventing the formation of a zone of steam or vapor about the balls.

7. In an apparatus of the class described, the combination of a cylindrical furnace for heating metal balls, a quenching drum associated with said furnace, means for revolving the drum and furnace, means in the furnace and drum for feeding a series of balls longitudinally of the furnace and drum respectively in single layer formation 90 as said furnace and drum are revolved to insure equal and proper treatment of all the balls of a series, means for directing the balls of a series from the furnace to the quenching drum, and a device extending 95 into the revolving quenching drum and extending adjacent the point where the balls of a series are received by the quenching drum for forcing a stream of liquid against the balls of a series as they are rotated and 100 preventing the formation of a zone of steam or vapor about the balls.

8. In an apparatus of the class described, the combination of a cylindrical furnace for heating metal balls, a quenching drum 105 associated with said furnace, means for revolving the drum and furnace, means in the furnace and drum for feeding a series of balls longitudinally of the furnace and drum respectively in single layer formation 110 as said furnace and drum are revolved to insure equal and proper treatment of all the balls of a series, means for directing the balls of a series from the furnace to the quenching drum, said means comprising a 115 spout entering the end of the quenching drum, and a device extending into the revolving quenching drum and extending adjacent the point where the balls of a series 120 are received by the quenching drum for 125

130

forcing a stream of liquid against the balls of a series as they are rotated and preventing the formation of a zone of steam or vapor about the balls.

- 5 9. In an apparatus of the class described, the combination of a cylindrical furnace for heating metal balls, means for feeding a measured quantity of balls to the furnace, a tank below the furnace, a quenching drum in said tank, means for revolving the furnace and drum, spiral feeding devices in the furnace and drum for feeding the said measured quantity of balls longitudinally of the furnace and drum respectively in single layer formation as said furnace and drum are revolved to insure equal and proper treatment of all the balls of the measured quantity, means for directing the measured quantity of balls from the furnace 10 to the end of the drum at a point in the latter within the spiral feeding device, and a nozzle extending into the end of the quenching drum adjacent the point within the spiral feeding devices, where the balls 15 are received for forcing a stream of liquid directly upon the balls as they are rotated and preventing the formation of a zone of steam or vapor about the balls.

- 10 10. In an apparatus of the class described, the combination of a cylindrical furnace for heating metal balls, means for feeding a measured quantity of balls to the furnace, a tank below the furnace, a quenching drum in said tank, means for revolving the furnace and drum, spiral feeding devices in the furnace and drum for feeding the said measured quantity of balls longitudinally of the furnace and drum respectively in single layer formation as said furnace and drum 15 are revolved to insure equal and proper treatment of all the balls of the measured quantity, means for directing the measured quantity of balls from the furnace to the end of the drum at a point in the latter 20 within the spiral feeding device, and a nozzle having a flattened end portion, extending into the end of the quenching drum adjacent the point within the spiral feeding devices where the balls are received for forcing a stream of liquid directly upon the balls 25 as they are rotated and preventing the formation of a zone of steam or vapor about the balls.

11. In an apparatus of the class described, 55 the combination of a cylindrical furnace for heating metal balls, a quenching drum associated with said furnace, means for revolving the drum and furnace, means in the furnace and drum for feeding a series of 60 balls longitudinally of the furnace and drum respectively in single layer formation as said furnace and drum are revolved to insure equal and proper treatment of all the balls of a series, means for directing the 65 balls of a series from the furnace to the

quenching drum, a device extending into the revolving quenching drum and extending adjacent the point where the balls of a series are received by the quenching drum for forcing a stream of liquid against the balls of a series as they are rotated and preventing the formation of a zone of steam or vapor about the balls, and means for discharging the balls from the quenching drum as the latter revolves.

70 12. In an apparatus of the character described, the combination of a cylindrical furnace, a tank below the same, a cylindrical quenching drum in said tank, a measuring feeder at one end of the furnace, means for revolving the furnace and causing the feeder to scoop up a measured quantity of balls and deliver them to the furnace, means within the furnace for feeding the measured quantity of balls longitudinally in single layer 75 formation, a chute connecting the furnace and drum for delivering the measured quantity of balls from the furnace to the quenching drum after they have been properly heated, and means extending into the end of the quenching drum for forcing a stream of liquid upon the measured quantity of balls 80 as they are delivered to the drum.

85 13. In an apparatus of the character described, the combination of a cylindrical furnace for heating metal balls, a quenching drum for hardening the metal balls, a measuring feeder connected to one end of the cylindrical furnace to feed a measured quantity of balls to the furnace, a spiral rib 90 within the furnace to feed the measured quantity of balls longitudinally in single layer relation to insure uniform heating of all the balls, means for directing such measured quantity of balls from the furnace to the quenching drum after they have been heated, a spiral feeder within the drum to insure a single layer relation of the balls 95 as they are moved longitudinally of the quenching drum, and means for rotating the furnace and the drum.

100 14. In an apparatus of the character described, a quenching tank, a quenching drum within said tank, a spiral rib within said drum for maintaining a predetermined number of heated balls in single layer formation and moving them longitudinally of said drum, means for rotating the drum and a nozzle extending into the end of the drum 105 for directing a stream of liquid upon said balls while they are individually rotated in said single layer formation and preventing the formation of a zone of steam or vapor about said balls.

115 15. In an apparatus of the character described, a quenching tank, a quenching drum within said tank, a spiral rib within said drum for maintaining a predetermined number of heated balls in single layer formation and moving them longitudinally of said 120

125 balls.

drum, means for rotating the drum and a nozzle extending into the end of the drum for directing a stream of liquid upon said balls while they are individually rotated in 5 said single layer formation and preventing the formation of a zone of steam or vapor about said balls, and means for varying the temperature of the liquid delivered by said nozzle.

10 16. In an apparatus of the character described, the combination of a cylindrical furnace, a quenching tank below said furnace, a quenching drum within said tank, and means for insuring the heating and 15 quenching of the balls in single layer formation, comprising a measuring feeder to deliver to the furnace upon rotation thereof

a measured quantity of balls and spiral ribs in the furnace and quenching drum spaced to accommodate such measured quantity of 20 balls in single layer and for moving the measured quantity of balls longitudinally of the furnace and drum while in such single layer formation, and a nozzle extending into the quenching drum at the point where the 25 balls are delivered to the drum for forcing liquid directly and equally upon the balls.

In testimony whereof, I have signed my name to this specification, in the presence of two subscribing witnesses.

OTTO W. SCHAUM.
